UNITED STATES PATENT OFFICE.

HERMAN FRASCH, OF CLEVELAND, OHIO.

FURNACE FOR THE MANUFACTURE OF CARBON.

SPECIFICATION forming part of Letters Patent No. 281,046, dated July 10, 1883.

Application filed January 12, 1883. (No model.)

To all whom it may concern:

Be it known that I, HERMAN FRASCH, of Cleveland, in the county of Cuyahoga and State of Ohio, have invented certain new and useful 5 Improvements in Furnaces for the Manufacture of Carbon; and I do hereby declare the following to be a full, clear, and exact description of the invention, such as will enable others skilled in the art to which it appertains 10 to make and use the same.

My invention relates to an improvement in furnaces for the manufacture of carbon for electric-light carbons and other purposes.

In the accompanying drawings, Figure 1 is 15 a view in front elevation. Fig. 2 is a plan view. Fig. 3 is a transverse section, and Fig. 4 is a vertical longitudinal section.

A represents the ash-pit, and B the fire-box door. The ash-pit communicates with two 20 flues, C C', which extend to the rear end of the furnace and then back and forth, forming return-flues, and having their exit in the escape-flues D D' at the front of the furnace, where they merge into the stack or chimney E. The 25 hearth of the furnace is constructed of the tilings a, which are placed directly over the flues C C'.

Upon the tilings a is placed a layer of asbestos, b, and upon the latter are placed the 30 tilings c, which are laid to break joints with the lower tilings, a. The arch F is covered with sand d, and the walls strengthened by the tie-rods e. At the front of the furnace is located the charging-opening G, provided with 35 a door, G'. This door is located a sufficient distance above the hearth or floor of the furnace to allow of the proper charging of the furnace.

At the sides and end of the furnace are the 40 doors H, which are placed on a level with the hearth or floor for the removal of the carbon. An escape-pipe, I, communicates with the upper portion of the furnace-chamber, and is provided with a stop-cock or valve, i. A pipe, 45 J, connects with the pipe I and leads beneath the grate of the fire-box. Pipe J is provided with a stop-cock or valve, j. The lower end of the chimney or stack is provided with a damper, K.

Having described the construction and relative arrangements of my improved furnace, I

will now describe its operation: I take distilled hydrocarbon of high density, obtained by the distillation of petroleum or other hydrocarbon oils, and mix the same with sulphuric 55 or nitric acid. After the furnace has been heated, all of the doors being closed, the charging-door is opened, and the compound is charged into the furnace to the proper depth. When the temperature reaches about 300° 60 Fahrenheit, the mass being quite liquid, reaction begins to take place, the hydrogen of the hydrocarbon combining with the oxygen of the acid if sulphuric acid is used, or steam and nitrogenous compounds when nitric acid 65 is used. This reaction tends to stiffen the whole mass, so that it becomes quite hard even before the temperature of 500° Fahrenheit is reached. By continuing the operation and gradually increasing the temperature to, say, 70 1000° Fahrenheit, or more, all of the decomposition products, being volatile, are driven off, leaving a carbon coke upon the hearth of the furnace almost chemically pure, quite dense and dry, and easily removed, which is 75 effected by opening the side doors and inserting a slice-bar beneath the mass, breaking it up into pieces and removing them through the side doors. In charging the furnace the damper K is opened to conduct the escaping flame into 80 the chimney, and thus not interfere with the workmen. The gases generated in the furnace may be allowed to escape, or be conducted to the ash-pit and burned. The quantity obtained by the process described is a large percentage 85 of the carbon originally employed. The sludge oils and acid compounds which are drawn off in the ordinary treatment of petroleum distillates may be subjected to the same treatment, in which case the same reaction 90 takes place and the same carbon product obtained, thereby very profitably utilizing what have been heretofore regarded as the waste products of an oil-refinery. The furnace is constructed so that the heat will evenly be 95 distributed beneath the hearth, and the latter is made comparatively thin so that the heat may readily be transmitted to the charge. By means of the two layers of tiling arranged to break joints and the intervening layer or 100 packing of asbestos a perfectly-tight hearth or floor is insured.

I make no claim in this application to the process described, as such subject-matter is described and claimed in my application filed October 27, 1881.

5 Having fully described my invention, what I claim as new, and desire to secure by Letters Patent, is—

1. A furnace for the manufacture of carbon, constructed with a flat floor or hearth composed of tiling with packed joints and capable of retaining a liquid or semi-liquid substance thereon, flues extending beneath the entire floor, discharging doors located on a level with the hearth or floor, and a charging-door located above the level of the hearth or floor, substantially as set forth.

2. In a furnace for the manufacture of carbon, the floor or hearth consisting of the layers of tiling and the intervening packing of asbestos, substantially as set forth.

3. A furnace for the manufacture of carbon, having a hearth or floor constructed of two layers of tiling, arranged to break joints, and an intervening packing of asbestos, substantially as set forth.

20 In testimony whereof I have signed this specification in the presence of two subscribing witnesses.

25 HERMAN FRASCH.
